CLAIM

The ornamental design for a display screen or portion thereof with animated graphical user interface for multi-player card game, as shown and described.

DESCRIPTION

FIG. 1 is a top plan view of a display screen or portion thereof with animated graphical user interface for multi-player card game showing the first image in a sequence; FIG. 2 is a top plan view of the second image thereof; and, FIG. 3 is a top plan view of the third image thereof.

The appearance of the animated images sequentially transitions between the images shown in FIGS. 1-3. The process or period in which one image transitions to another forms no part of the claimed design.

The broken lines in the Figures show a display screen or portion thereof and elements of an animated graphical user interface which form no part of the claimed design.
